UNITED STATES PATENT OFFICE.

MICHAEL EVANS, OF PHILADELPHIA, PENNSYLVANIA.

FAULT DETECTOR FOR GAS ENGINES.

Application filed July 1, 1922. Serial No. 572,196.

To all whom it may concern:

Be it known that I, MICHAEL EVANS, a citizen of the United States, residing at Philadelphia, in the county of Philadelphia 5 and State of Pennsylvania, have invented certain new and useful Improvements in Fault Detectors for Gas Engines, of which the following is a specification.

My invention relates to fault detectors for 10 gas engines, and specifically considered it relates more particularly to a device adapted to be attached to the cylinder head of a gas engine, preferably at the place where the spark plug is usually located, whereby various motor troubles and the causes thereof 15 may be readily detected and ascertained, such as faulty spark plugs, poor compression, or improper mixtures of the gas and air.

The principal object of my invention is to 20 provide a simple and efficient device adapted to be mounted in the cylinder head of a gas engine which will permit the observation, when desired, of the conditions existing within the cylinder of the engine during the 25 operation thereof. A further object of my invention is to provide a device of the character described of such construction and arrangement that the device itself will be protected from strains and fouling during the 30 normal operation of the engine, that is, when it is not desired to observe the conditions within the cylinder.

The nature and characteristic features of my invention will be more readily understood 35 from the following description, taken in connection with the accompanying drawings forming part hereof, in which

Figure 1 is a vertical, central, sectional view of a fault detector for gas engines embodying the main features of my invention, the same being shown mounted in the cylinder head of a gas engine of any preferred type, and having a spark plug of usual construction mounted on the device;

Fig. 2 is a top or plan view thereof;

Fig. 3 is a horizontal section taken approximately on the line 3—3 of Fig. 1; and

Fig. 4 is a fragmentary side elevation illustrating certain details of the device.

Referring to the drawings, in the particular embodiment of my invention therein shown, 5 is a casing or housing having a threaded portion 6 which is screwed into a complementally threaded opening in the cylinder head 7 of the gas engine in connection with which the device is used. Mounted

within the housing 5 is a plug member 8 having an extension 9 which is provided with a passageway 10 communicating with the interior of the cylinder. A nut 11 is 60 threaded on the lower end of the extension 9 of the plug 8 and bears against the lower end of the threaded portion 6 of the housing 5, thereby serving to hold the plug member 8 within the housing 5. A flaring ground 65 joint 12 may be provided between the upper end of the plug member and the housing 5 to prevent the escape of gases during the operation of the engine.

A spark plug 13 of any preferred type is 70 mounted at the upper end of the plug member 8, the interior of said upper end of the plug member 8 being threaded complementally to the threaded portion 14 of the spark plug 13. A chamber 15 is provided in the 75 interior of the plug member 8 below the lower end of the threaded portion 14 of the spark plug 13, this chamber being in communication, by means of the passageway 10, hereinbefore described, with the interior of 80 the cylinder in connection with which the device is used.

On opposite sides of the housing 5 there are provided threaded extensions 16 arranged in alinement with each other, and each of said threaded extensions 16 has mounted on the end thereof a threaded gland 17 which serves to hold a glass window member 18 on the end of the extension 16. Suitable gaskets 19 and 20 are provided to prevent the escape of gases past the glass window members 18. As before noted, the extensions 16 are hollow, that is, the same have passageways 21 extending from the plug member 8 to the window members 18. The plug member 8 is also provided with apertures 22 in the side walls thereof, these apertures being so disposed in alinement with each other as to be brought into communication with the passageways 21 of the extensions 16, as illustrated in Fig. 1 of the drawings.

The plug member 8 is also provided with an extending handle 23, whereby the plug member may be turned ninety degrees so as to close off the communication between the apertures 22 of said plug member and the passageways 21, as illustrated in Fig. 3 of the drawings. The plug member may also be provided at its upper end with an extending portion 24, which may be provided with a sector slot 25 which is engaged by

means of a pin 26, the extent of the sector slot 25 being such as to limit the motion of the plug member 8 to a fully opened or a fully closed position.

5 The operation of the device may now be readily understood. When the plug member 8 is in the position shown in Fig. 1 of the drawings, and the engine is operating, any faults occurring in the cylinder (the interior of which is in communication, by means of passageways 10, with the chamber 15) will be readily apparent to the observer. For example, if the spark plug is not functioning properly, either through a fault in the plug itself or a fault in the ignition system, this will be readily apparent to the observer, for the reason that no spark between the terminals of the spark plug will be perceptible, nor will any explosion of the contents of the cylinder take place. On the other hand, if the fault be due to a weak compression arising from any of the common causes of such faults, or from too lean or too rich a mixture of gas and air within the cylinder, this condition will be readily observed by reason of differences in the appearance or "color" at the time of the explosion of the gaseous mixture within the cylinder. It will also be readily understood that where the device is employed, adjustments of the carburetor will be greatly facilitated, as the result of changes in the adjustment may be observed by the operator as the same are made.

35 It will also be readily understood that during the normal operation of the engine, when it is not desired to observe the conditions existing within the cylinder of the engine, by turning the plug member 8 to the position shown in Fig. 3 of the drawings, communication between the chamber 15, in the interior of the plug member 8, and the passageways 21 of the extension 16 will be cut off, and thereby the glass window members 18 will be protected against the constant hammering which would otherwise result and which may cause breakage, and the same will also be protected against contamination from carbon deposits which would obscure the observation at the time the same is desired.

By arranging the window members 18 in alinement with each other, if the same should become fouled, this condition may be readily observed by turning the plug member 8 to the open position and looking through said windows, with the assistance of a light if required.

Having thus described the nature and characteristic features of my invention, what I claim as new and desire to secure by Letters Patent is:

60 1. A fault detector for gas engines comprising a device having the interior thereof 65 in communication with the interior of the

engine cylinder, said device being interiorly threaded to receive a spark plug of the ordinary type, and a window member mounted on the device, the device having a passageway extending from said window member 70 to the interior, and means for cutting off the communication between the interior of the device and the passageway extending from the window member.

2. A fault detector for gas engines comprising a device having the interior thereof 75 in communication with the interior of the engine cylinder, said device being interiorly threaded to receive a spark plug of the ordinary type, a pair of window members 80 mounted on the device in alinement with each other, the device having passageways extending from said window members to the interior, and means for cutting off the communication between the interior of the device 85 and the passageways extending from the window members.

3. A fault detector for gas engines comprising a housing member mounted in the cylinder of the engine, a plug member 90 mounted in said housing having the interior thereof in communication with the interior of the engine cylinder, said plug member being interiorly threaded to receive a spark plug of the ordinary type, and a window member 95 mounted on said housing, said housing having a passageway extending from said window member to the plug member, the plug member having an aperture extending to the interior thereof, and said aperture 100 being adopted to register with said passageway.

4. A fault detector for gas engines comprising a housing member mounted in the cylinder of the engine, a plug member 105 mounted in said housing having the interior thereof in communication with the interior of the engine cylinder, said plug member being interiorly threaded to receive a spark plug of the ordinary type, and a pair of window members 110 mounted on said housing in alinement with each other, said housing having passageways extending from said window members to the plug member, the plug member having apertures extending to the interior thereof, and said apertures being adapted to register with said passageways.

5. A fault detector for gas engines comprising a housing member mounted in the 120 cylinder of the engine, a plug member mounted in said housing having the interior thereof in communication with the interior of the engine cylinder, said plug member being interiorly threaded to receive a spark plug of the ordinary type, a window member 125 mounted on said housing, said housing having a passageway extending from said window member to the plug member, the plug member having an aperture extending 130

to the interior thereof, said aperture being adapted to register with said passageway, and means for rotating the plug member to thereby cut off the communication between 5 the interior of the plug member and said passageway.

6. A fault detector for gas engines comprising a housing member mounted in the cylinder of the engine, a plug member 10 mounted in said housing having the interior thereof in communication with the interior of the engine cylinder, said plug member being interiorly threaded to receive a spark plug of the ordinary type, a pair of window 15 members mounted on said housing in alignment with each other, said housing having passageways extending from said window members to the plug member, the plug member having apertures extending to the interior 20 thereof, said apertures being adapted to register with said passageways, and means for rotating the plug member to thereby cut off the communication between the interior of the plug member and said passageways.

25 7. A fault detector for gas engines comprising a housing member mounted in the cylinder of the engine, a plug member mounted in said housing having the interior thereof in communication with the interior 30 of the engine cylinder, said plug member being interiorly threaded to receive a spark plug of the ordinary type, a window member mounted on said housing, said housing

having a passageway extending from said window member to the plug member, the 35 plug member having an aperture extending to the interior thereof, said aperture being adapted to register with said passageway, means for rotating the plug member to thereby cut off the communication between 40 the interior of the plug member and said passageway, and means for limiting the positions of said plug member.

8. A fault detector for gas engines comprising a housing member mounted in the 45 cylinder of the engine, a plug member mounted in said housing having the interior thereof in communication with the interior of the engine cylinder, said plug member being interiorly threaded to receive a spark 50 plug of the ordinary type, a pair of window members mounted on said housing in alignment with each other, said housing having passageways extending from said window members to the plug member, the plug 55 member having apertures extending to the interior thereof, said apertures being adapted to register with said passageways, means for rotating the plug member to thereby cut off the communication between 60 the interior of the plug member and said passageways, and means for limiting the positions of said plug member.

In testimony whereof, I have hereunto signed my name.

MICHAEL EVANS.
